SLUG CASTING MACHINE

Luther E. Morrison, New York, N. Y., assignor to
 Mergenthaler Linotype Company, a corporation
 of New York

Application June 23, 1934, Serial No. 732,032

15 Claims. (Cl. 199—49)

This invention relates to slug casting machines, wherein the slugs are cast against a line of matrices while supported in a hand stick wherein they are composed by hand. As is well known, 5 the intaglio characters occupy an inverted position on the matrix bodies and are punched or otherwise formed in the bottoms of routing notches cut across the casting edges of the matrices.

10 There are three different kinds of matrices now in general use, those of one kind having their characters located for "top alinement", those of another kind for "base alinement", and those of still another kind for "center alinement". It so happens that the matrices of the 15 three kinds differ in external form and hence require the use of as many different kinds of hand sticks for their composition, but even if the matrices were of the same external form (as they might be), it would still be necessary to employ different kinds of hand sticks owing to the different systems of alinement. Moreover, as a further disadvantage, the matrices of one kind or 20 whose characters are located for one system of alinement can only be used when that particular system is to be followed.

25 The present invention is directed to certain improvements wherein matrices intended for one system of alinement may be composed in the hand stick not only in accordance with that particular system of alinement, but also in accordance with a different system of alinement, thus rendering it possible to employ the same kind of 30 matrices and the same kind of hand stick for two different systems of character alinement. In the present instance, the matrices selected for the dual alinement are of the Ludlow variety, that is to say, those commonly employed in machines sold under the name "Ludlow" and whose 35 characters are normally intended for center alinement. According to this invention, such matrices may be composed in the hand stick for center alinement or for base alinement, as may be desired, the hand stick and the matrices being 40 constructed with this end in view.

45 The hand stick herein illustrated is one particularly adapted for use in a machine of the character disclosed in the copending application of Anthony J. Stouges, Serial No. 731,832, filed June 22, 1934, although obviously it could be made 50 for use in the regular commercial machine sold under the trade-mark Linotype, or even in the Ludlow machine itself.

55 In the accompanying drawings, two different embodiments of the invention have been shown

by way of example, and obviously many modifications and alterations may be made therein which will still be comprised within the spirit of the invention. It should be understood, therefore, that the invention is not limited to any particular form or embodiment except insofar as such limitations are specified in the appended claims.

Referring to the drawings:

Fig. 1 is a rear elevation of the improved hand stick, showing a line of matrices composed 10 therein;

Fig. 2 is an end elevation of the hand stick shown in Fig. 1, looking from left to right;

Fig. 3 is a transverse section taken on the line 15 3—3 of Fig. 1;

Fig. 4 is a front elevation of a group of matrices of different fonts, with their characters in common base alinement;

Fig. 5 is a rear perspective of two matrices of 20 different fonts;

Fig. 6 is a view similar to Fig. 1 of a modified form of hand stick;

Fig. 7 is a transverse section taken on the line 25 7—7 of Fig. 6;

Fig. 8 is a view similar to Fig. 7, but showing the matrices in a different position;

Fig. 9 is a front elevation of a portion of the modified form of hand stick, showing matrices 30 of different fonts composed therein with their characters in common base alinement; and

Fig. 10 is a rear perspective view of two matrices of different fonts.

Referring first to the embodiment shown in Figs. 1 to 5, the matrices M (of the Ludlow variety as before stated) are of the customary form except for the transverse notches R cut through the rear or noncasting edges. Thus, the matrices are formed in their front or casting edges with inverted intaglio characters M¹ punched in the bottoms of transverse routing notches M², the characters, as usual, being located on the matrix bodies for center alinement. Moreover, at their rear edges the matrices are provided with supporting ears M⁴ projecting in opposite directions from top and bottom edges m and m¹, which latter sometimes converge toward the front or casting edges to facilitate the insertion of the matrices into the hand stick from the rear.

As previously stated, the hand stick A is of the kind disclosed in the Stouges application Serial No. 731,832, being of generally rectangular form and open at both the front and rear. As shown, the stick comprises parallel side walls A¹ and A², parallel end walls A³ and A⁴, and a line clamping 55

member A⁵ (shaped like a matrix), the latter being acted upon by a hollow thumb screw A⁶ threaded in the end wall A⁴ and having a stud A⁷ passing loosely through and beyond the thumb screw for engagement with one of the line clamping jaws of the machine between which the hand stick is located during casting.

As ordinarily constructed, the side walls A¹ and A² are spaced apart for a distance corresponding to that between the top and bottom edges m and m¹ of the matrices, so that when the matrices are composed in the hand stick they are held against endwise movement and are positioned for center alinement of the characters as normally intended.

15 In accordance with this invention, however, the side walls A¹ and A² are more widely spaced apart (see Fig. 3), this wider spacing being made great enough to permit the individual matrices to be shifted endwise relatively to each other to adapt 20 their characters M¹ for base alinement (see Fig. 4).

In the use of the hand stick, the matrices are composed therein in the usual way with their bottom edges m¹ banking against the lower side 25 wall A² and as the matrices are thus positioned in the stick the characters M¹ are located for center alinement. If that particular system of alinement is to be followed then the operator needs only to tighten up the thumb screw A⁶ to 30 hold the matrices in their assembled condition.

When the matrices are to be located in the stick for base alinement, they are composed in the same way, namely, by allowing their lower edges m¹ to bank or rest upon the lower side wall A², but 35 thereafter the matrices are shifted relatively to each other toward the upper wall A¹ until the lower walls R² of the notches R (before referred to) are brought into register or alinement as shown in Fig. 1. In this connection it is pointed 40 out that the location of the notch walls R² varies according to the font size of the matrix characters such that when the walls are in alinement the characters will aline at their bases as shown in Fig. 4 and by the dotted lines in Fig. 1. 45 It will here be noted that the matrices bearing characters of the largest size, like the large matrix shown at the left in Fig. 1, do not need to have any endwise movement, being allowed to remain with their lower edges m¹ upon the lower wall A² 50 of the hand stick. The same is true of blank matrices or spacers, such as those designated N in Fig. 1.

As a means for effecting such alinement of the matrices in the hand stick, the latter is provided 55 with a straight bar or alining gage A⁸ which, after the matrices have been composed in the stick, is adapted to be placed in the notches R and fixedly supported when the matrices are shifted endwise. As a result, such shifting of the matrices brings 60 the lower walls R² of the notches R into contact with the lower edge of the alining bar and thus positions the matrices for base alinement as desired. After alinement the operator needs merely 65 to tighten up the thumb screw A⁶ to hold the matrices in their shifted position.

Since the matrices are originally composed with their lower edges m¹ resting upon the lower wall A² of the hand stick, which means that the lower 70 walls R² of the notches R will be out of registry (see Fig. 5), the notches R are made wide enough so that in the original composed position of the matrices the top walls R¹ will all aline or register with each other and thus permit the alining bar A⁸ 75 to be moved freely into the notches whether the

matrices are to be used for one system of alinement or the other.

While the bar A⁸ might be otherwise supported, or even made detachable if desired, it is shown in the embodiment under discussion as carried by 5 a pair of arms A⁹ pivoted by screw studs A¹⁰ to the end walls A³ and A⁴ of the stick. As thus mounted the alining bar during the composition of the matrices may be swung down to the dotted line position shown in Fig. 2 and later swung up 10 to the full line position shown in Fig. 2 where it remains during the slug casting operation.

When the bar A⁸ is to be used for effecting base alinement of the matrix characters, it is first swung up to its active position, as shown in Figs. 15 1 and 2, as permitted by the notches R whose upper walls R¹ are at the time in register, and the matrices thereafter shifted individually by hand to bring the lower walls R² of the notches into contact with the bar, or, better still, to tilt 20 the stick downwardly sufficiently so that all of the matrices as a whole may drop by gravity until arrested by the contact of the lower walls R² of the notches R with the bar after which, as before stated, the matrices are held in their 25 shifted position by the tightening up of the thumb screw A⁶.

The embodiment shown in Figs. 6 to 10 is precisely the same as that shown in Figs. 1 to 5, except that in this instance the alining bar designated A¹¹ is fixed to the upper wall A¹ of the hand stick and is arranged to cooperate with notches S cut in the top edges m of the matrices (see particularly Figs. 7 and 8). The notches S vary in depth in the same way as the notches R and for the same purpose, their bottom walls S¹ being positioned so that when brought into contact with the lower edge of the alining bar A¹¹ the characters M¹ of the matrices will be located for base alinement. It will be noted in Fig. 7 40 that the lower edge of the alining bar A¹¹ is arranged at such a distance from the bottom wall A² of the hand stick that the matrices may be inserted into the stick from the rear without interference. If the matrices are allowed to remain with their lower edges m¹ resting against the bottom wall A², their characters will be located for center alinement. On the other hand, if the matrices are shifted endwise toward the upper wall A¹ to bring the bottom walls S¹ of their notches S into contact with the lower edge 45 of the alining bar A¹¹, as shown in Fig. 8, the matrix characters M¹ will then be located for base alinement (see Fig. 9 and the dotted lines 50 in Fig. 6). As before, the matrices, when shifted in the manner described, are held in their shifted 55 position by tightening up the thumb screw A⁶.

While the invention has herein been shown and described in connection with Ludlow matrices, which may be set up in the hand stick for either center alinement or base alinement, it is obvious that the invention would extend to other kinds of matrices, or matrices which are to be used for other systems of alinement. For example, the matrices shown and described in the Stouges application Serial No. 731,832, before referred to, are normally intended for base alinement and yet, according to the present invention, they could be altered in similar fashion to adapt the characters for center alinement if desired. The same principle applied to matrices such as are used in the regular commercial linotype machines and which are normally intended for top alinement, it being possible to modify such matrices by the use of notches and an alining bar to adapt their 75

characters either for center alinement or for base alinement.

Having thus described my invention, what I claim is:

- 5 1. In or for a slug casting machine, a hand stick for composing a line of matrices, said matrices being capable of relative transverse movement in the hand stick and being formed each with two alining surfaces, one for base alinement 5
10 and the other for a different alinement, and means on the stick adapted to cooperate with said alining surfaces to determine the relative positions of the matrices for one alinement or the other as desired.
- 15 2. In or for a slug casting machine, a matrix composing hand stick equipped with an alining member, and a line of matrices of different fonts assembled therein and whose characters are normally intended for other than base alinement, 10
20 said matrices being formed with alining surfaces located at different points on matrices of different font sizes and engageable with said alining member for composition in different relative positions with their characters in base alinement.
- 25 3. In or for a slug casting machine, a matrix composing hand stick equipped with an alining bar, and a line of matrices of different fonts assembled therein and whose characters are normally intended for other than base alinement, 25
30 the matrices being formed with recesses to receive said alining bar and the recesses varying in depth between fonts, whereby the matrices may be alined by the bar in different relative positions with their characters in base alinement.
- 35 4. A hand stick according to claim 2, wherein the alining member is fixed, and each matrix is formed in an edge adjacent the casting edge with a notch adapted to fit over the alining member, the notches varying in depth in matrices of 30
40 different fonts.
5. A hand stick according to claim 2, wherein the alining member is movable into and out of operative position, and the matrices of different fonts are formed in the edges opposite their casting edges with recesses of different widths adapted to receive the alining member and render the matrices capable of relative transverse movement to bring their characters into common base alinement.
- 50 6. In or for a slug casting machine, a matrix composing hand stick equipped with a movable alining bar, a line of matrices of different fonts composed therein and whose characters may be located for different systems of alinement, recesses formed in the edges opposite the casting edges of the matrices, said recesses varying in width in matrices of different fonts, whereby the matrices may be composed in the stick for one system of alinement and the alining bar moved 40
50 into position to seat in the recesses of all matrices, the matrices being thereafter movable relatively to one another to bring a wall of each recess into engagement with the bar to locate the matrix characters for a different system of alinement.
- 65 7. In or for a slug casting machine, a matrix composing hand stick having parallel side and end walls, one of said side walls presenting an alining surface and the other being equipped with an alining bar, a line of matrices of different fonts composed in the stick and whose characters may be located for different systems of alinement, the matrices at one end being formed 55
70 to engage said alining side wall and locate the matrix characters in accordance with the system of alinement for which they are normally intended and the matrices being formed in their opposite ends with notches varying in depth in matrices of different fonts to engage with said alining bar for locating their characters in accordance with a different system of alinement.
8. In or for a slug casting machine, a matrix composing hand stick having parallel side and end walls, one of said side walls presenting an alining surface, a line of matrices composed in the stick and having alining surfaces to engage said side wall and locate the matrix characters in accordance with the system of alinement for which they are normally intended, said matrices 10
15 being formed with other alining surfaces located at different points on different matrices, and an alining bar arranged in the stick and engageable with said other alining surfaces in determining the relative positions of the matrices to locate 20
25 their characters in accordance with a different system of alinement.
9. In or for a slug casting machine, a matrix composing hand stick equipped with an alining member for the composition of a line of matrices 25
30 therein of different font sizes, said matrices being formed with alining surfaces located in different positions on matrices of different fonts and engageable with said alining member to locate the characters of the matrices in accordance 30
35 with a system of alinement other than that for which they are intended.
10. In or for a slug casting machine, a matrix composing hand stick containing a line of matrices of different font sizes, said matrices differing in form as between the fonts other than by size of character, and said hand stick having means to cooperate with the matrices of the different forms and locate their characters in accordance with a system of alinement other 40
45 than that for which they are normally intended.
11. In or for a slug casting machine, a matrix composing hand stick containing a line of matrices of different font sizes, said matrices differing in form as between the fonts other than by size of character, and said hand stick having means to cooperate with the matrices of the different forms and locate their characters in accordance with one or another system of alinement.
12. In or for a slug casting machine, a matrix composing hand stick containing a line of matrices of different font sizes, said matrices differing in form as between the fonts other than by size of character, and said hand stick being provided with an alining surface to cooperate with the matrices of the different forms and locate their characters in accordance with a system of alinement other than that for which they are normally intended.
13. In or for a slug casting machine, a matrix composing hand stick containing a line of matrices of different font sizes, said matrices differing in form as between the fonts other than by size of character, and said hand stick being provided with two alining surfaces to cooperate with the matrices of the different forms, one to locate the matrix characters in accordance with the system of alinement for which they are normally intended and the other to locate them in accordance with a different system of alinement.
14. In or for a slug casting machine, a matrix composing hand stick containing a line of matrices of different font sizes, said matrices be- 70
75

ing formed with alining surfaces differing in location as between the fonts, and said hand stick being provided with an alining bar to cooperate with the alining surfaces of the matrices of the different fonts and locate their characters in accordance with a system of alinement other than that for which they are normally intended.

15. In or for a slug casting machine, a matrix composing hand stick containing a line of matrices of different font sizes, said matrices being formed with alining surfaces occupying the same

location as between the fonts and with other alining surfaces differing in location as between the fonts, and said hand stick being provided with two alining surfaces to cooperate with the respective alining surfaces of the matrices, one 5 to locate the matrix characters in accordance with the system of alinement for which they are normally intended and the other to locate the matrix characters in accordance with a different system of alinement.
